UNITED STATES PATENT OFFICE.

ALPHONS M. KUHL, OF CARROLL, IOWA.

ADJUSTABLE SHAFT.

1,079,865.

Specification of Letters Patent. Patented Nov. 25, 1913.

Application filed January 20, 1913. Serial No. 743,175.

To all whom it may concern:

Be it known that I, ALPHONS M. KUHL, a citizen of the United States, residing at Carroll, in the county of Carroll and State of Iowa, have invented a new and useful Adjustable Shaft, of which the following is a specification.

This invention relates to improvements in adjustable shafts.

10 The primary object of the invention is to provide a mechanism, in which the shaft may be moved laterally with respect to the thills, while the vehicle is moving, in order that the draft animal may traverse a path 15 other than the middle of the beaten path, the vehicle maintaining its line of travel in the beaten path.

With the foregoing and other objects in view which will appear as the description 20 proceeds, the invention resides in the combination and arrangement of parts and in the details of construction hereinafter more fully described and claimed, it being understood that changes in the precise embodiment of the invention herein disclosed, can be made within the scope of what is claimed, 25 without departing from the spirit of the invention.

In the drawings:—Figure 1 is a top plan view, the shaft being shown in dotted lines as moved laterally with respect to the thills. Fig. 2 is a bottom plan view. Fig. 3 is a perspective view of the yoke which is secured to the shaft supporting bar and which 35 embraces bars which connect the thills. Fig. 4 is a section taken on the line 4—4 of Fig. 1. Fig. 5 is a longitudinal section. Fig. 6 is a detail view of the latch member.

In the drawings 10 designates the thills 40 which are connected by bars 11. The under faces of the thills are provided with straps 12, a rod 14 connecting the straps and being disposed parallel with the bar 11. The face 15 of the bar 11 is formed with a groove 45 16 which receives the rib 17 of the shaft supporting bar 18, a swingletree 19 being mounted on said bar. A plurality of brackets 20 are disposed on the under face of the bar 11, said brackets pivotally supporting 50 the curved arms 21, the terminals 22 of which are provided with elongated slots 24, said slots receiving pins 25 carried by the shaft 26, the pins 25 being supported by brackets 27 which are secured to the shaft. 55 Thus the shafts are supported for free sliding movement with respect to the bars.

The rib 17 is maintained in the groove 16 by means of the yoke 29 which is formed with the extension 30 which embraces the rod 14, the extension 31 extending transversely of the under face of the bar 11, being connected to bar 18, a strap 32 being secured to the adjacent portion of the shaft, attention being called to the fact that the terminals of this strap may be bent to form the brackets which support the pins 25. A plurality of vertically disposed posts 32' connect the portions 33 and 34 of the yoke, said posts being braced by the terminals 35 and 36 of the plate 37, this plate 37 being formed with the extension 38 which has an end portion 39 resting upon the bar 11 and the portion 40 pivotally supporting the swingletree 19. The bar 18 and the shafts supported thereby are disposed for sliding movement 70 with respect to the bar 11, the bars as before stated being held together by the yoke which embraces the rod 14. Thus the shafts may be moved to either side of the vehicle in order to allow the draft animal to travel a 80 path other than the central path between the wheel ruts. The yoke is held in its adjusted position by the latch member 39 the terminal 40' of which is offset and provided with the extension 41 which when the latch 85 member is brought to locking position enters an opening 42 in the strap 43, said strap 43 being secured to the bar 11 and having its offset terminal 44 secured to the thills, the other terminal 45 of the latch member 90 being offset and disposed at an angle with respect to the body portion 39', the same being arranged to embrace the bar 14, being manipulated by the terminal 45. When this latch member is moved to embrace the bar 95 14 the same will draw the shafts carrying bar in contact with the bar 11 to maintain the shafts carrying member in fixed position with relation to said bar. The latch member is provided adjacent its offset terminal 40' 100 with trunnions 46 which are supported within the sleeves 47 formed integral with or secured to the plates 37 of the yoke, the latch member thus being pivotally supported by said yoke, the same being sufficiently 105 resilient to engage the rod 14, and be held in rigid contact or engagement with the same. Thus it will be noted that the shafts carrying bar may be moved laterally with respect to the vehicle and maintained in any desired 110 position with respect to the bar which is supported by the thills. It will be noted that

the construction is such that the shifting of the shafts carrying members and the locking of the same in position may be accomplished while the vehicle is in motion and while the driver is seated. It will also be noted that the entire structure is such as may be easily and economically manufactured and that the mechanism may be applied to vehicles now in use without materially altering their construction.

10 What is claimed is:—

1. A draft attachment, comprising a stationary bar supported by the thills of a vehicle, a bar disposed in sliding relation to the first mentioned bar, said second bar supporting the shafts, a rod connecting the thills, a yoke carried by the sliding bar and embracing said rod, and a latch member carried by said yoke for locking the same at 15 any point along said bar.

2. A draft attachment, comprising a stationary bar, supported by the thills of a vehicle, a bar disposed in sliding relation to the first mentioned bar, said bar supporting 20 the shafts, a link connection between the stationary bar and the shafts, and a yoke carried by the sliding bar, a rod connecting the thills, said yoke embracing said rod to maintain the sliding bar and the stationary bar in engagement.

3. A draft attachment, comprising a stationary bar, said bar being formed with a groove, a sliding shaft supporting bar, said bar being arranged with a tongue adapted 25 to enter the groove of the other bar, a link connection between the stationary bar and the shafts, a yoke secured to the sliding bar, a rod connecting the thills, the yoke being formed with extensions which embrace said 30 rod, a plate supported by said yoke and arranged to contact with the stationary bar, and a latch member pivotally supported by said yoke and arranged to contact with said rod, to lock the yoke against lateral movement thereon.

4. A draft attachment comprising a stationary bar connecting the thills of a vehicle, a bar disposed in sliding relation to the first mentioned bar, said bar supporting 35 the shafts of the vehicle, a curved slotted link pivotally supported by the stationary bar and having a sliding connection with the sliding bar, a yoke supported by the sliding bar, said yoke being formed with extensions, a rod connecting said thills and being embraced by said extensions, a plate

supported by said extensions and supported in contact with the stationary bar, an extension being formed integral with said plate and being extended above the sliding 60 bar to form a support for the swing tree, the plate adjacent said extension being bent to form bearings, and a latch member, said latch member being formed with trunnions which extend in said bearings, said latch 65 member being arranged to embrace said bar to lock the yoke against longitudinal movement on the bar.

5. A draft device comprising a stationary bar connecting the thills of a vehicle, a shaft 70 supporting bar disposed in sliding relation to the first mentioned bar, a link connecting the shafts supported by the stationary and sliding bars, said link having a pivotal connection with the stationary bar and a sliding connection with the shafts, a yoke secured to the sliding bar, a rod connecting the thills, said yoke being formed with extensions which embrace said rod, a plate supported by said yoke and arranged to contact with the stationary bar, and a latch member carried by said yoke and arranged to embrace said rod to hold the yoke against longitudinal movement on the rod.

6. A draft device comprising a bar connecting the thills of a vehicle, a bar disposed in sliding relation with the first mentioned bar, shafts supported by said bar, a yoke supported by said bar, posts supported by said yoke, a plate, the terminals of which embrace said posts, said plate intermediate its ends being formed with an extension which contacts with the stationary bar and which is disposed above the sliding bar to form a support for the swing tree arranged thereon, said plate on either side of said extension, being formed with bearings, a latch member formed with trunnions which extend within said bearings, the terminal of said latch member remote from the plate being offset, a rod connecting the thills, the terminal of said latch member being arranged to embrace said rod to maintain said yoke against longitudinal movement on said rod.

100 In testimony that I claim the foregoing as my own, I have hereto affixed my signature in the presence of two witnesses.

105 ALPHONS M. KUHL.
